ARM SLING

Eleanor R. Morris, 1260 W. 7th Drive,
Mesa, Ariz. 85202

Filed July 8, 1970, Ser. No. 23,864

Term of patent 14 years

Int. Cl. D24—05

U.S. Cl. D83—1

FIG. 1 is a front view of an arm sling showing my new design; and

FIG. 2 is a back view.

The broken lines representing the human form are shown for illustrative purposes only.

I claim:

The ornamental design for an arm sling, as shown and described.
